UNITED STATES PATENT OFFICE.

WILLIS H. SARGENT, OF ST. JOHNSBURY, VERMONT, ASSIGNOR TO THE
E. & T. FAIRBANKS & COMPANY, OF SAME PLACE.

DESIGN FOR A SCALE-BEAM SUPPORT.

SPECIFICATION forming part of Design No. 24,087, dated March 5, 1895.

Application filed December 29, 1894. Serial No. 533,360. Term of patent 14 years.

To all whom it may concern:

Be it known that I, WILLIS H. SARGENT, a citizen of the United States, residing at St. Johnsbury, in the county of Caledonia, State 5 of Vermont, have invented a certain new and original Design for a Scale-Beam Support, of which the following is a description, reference being had to the accompanying drawings and to the letters of reference marked thereon.

10 My invention relates to a new and original design for a support for scale beams.

The design is illustrated in the accompanying drawings, in which—

15 Figure 1 represents my design in side elevation. Fig. 2 is an end view of the same.

The beam support or stand consists of the rounded base portions B. Rising upward from the base piece is the pedestal C. Each pedestal is formed with a forked upper end, 20 each arm a of said fork being curved and joining the main part of the pedestal at b. From the point b two arms c are curved outwardly, one on either side to the point d, when they extend downward in a perpendicular line 25 to the point e. Thence a concaved portion f, unites each vertical arm to the horizontal part g. The entire appearance of the pedestal is vertical when looked at from the front, as in Fig. 1, but beginning at the point h, the lower

part of the pedestal begins to curve, first being formed on a concave curve i, then a convex curve k and then curved to form a loop l resting on the base B. From the loop the curve is upward, first slightly convex as at m and then on the exterior concave as at n, terminating in the enlarged portion o. On the interior of the loop however, the concave curve m is continued and meets the inside of the convex curve k in the enlarged portion p. From the sides of the loop l, downwardly 30 curved feet q extend, resting on the base B. Extending between the loops of either pedestal is the horizontal part formed, as shown, with the upper and lower parallel and substantially straight beams r r' joined at the 40 central portion by the part s formed in the manner indicated.

Having thus described my invention, what I claim, and desire to secure by Letters Patent, is—

50 The design for a scale beam support; substantially as described.

In testimony whereof I affix my signature in presence of two witnesses.

WILLIS H. SARGENT.
